EXPLOSIVE DEVICE

**Frederick R. Seavey, Alton, Ill., assignor to Olin Mathie-
son Chemical Corporation, East Alton, Ill., a corpora-
tion of Virginia**

Application September 29, 1954, Serial No. 459,110

3 Claims. (Cl. 102—27)

3 Claims. (CL. 102—27)

This invention relates generally to explosives and more particularly to a novel explosion-retarding coupler for lengths of detonating fuse.

It is desirable in some blasting operations particularly in quarries and in some surface mines to shoot successively several explosive charges which have been properly spaced over an area to be blasted without it being necessary for personnel to enter the area between shots. Detonation of these explosive charges located at various places in the area is accomplished by means of lengths of detonating fuse placed in the drill hole with the explosive charge and extending to a common trunk line of similar detonating fuse which leads to a position where it can be safely initiated. The simultaneous explosion of all the charges is undesirable because of the degree of earth vibration produced thereby so it is desirable to provide delay elements or explosion-retarding devices between the lengths of detonating fuse either in each branch line or at various points in the trunk line in order to fire the explosive charges successively. One such device which has been proposed for this purpose has a deflagrating charge butted up against one length of detonating fuse and an ignition mixture butted up against the other length of detonating fuse with a delay charge interposed therebetween. In this type of device the flame from the first length of fuse ignites the ignition mixture which in turn ignites the delay composition and the deflagrating charge. It has been found in practice, however, that such a device depending upon the flame of the burning detonating fuse for ignition is not entirely satisfactory because it frequently fails to ignite the second length of detonating fuse. In order to insure ignition of the second length, the ends of the lengths of detonating fuse must be butted up against the end of the ignition mixture. Such precise assembly is not always obtained in practice which might be at least partially responsible for the ignition failures. Moreover, considerable difficulty has been experienced in making such a device sufficiently waterproof for use at many blasting sites so it has been necessary for the manufacturer to supply a device having short lengths of detonating fuse inserted in each end thereof in order to insure waterproofness. It is undesirable to ship packages containing both an initiating charge and the quantity of secondary explosives in these so-called "fuse tails".

It is therefore an object of this invention to provide a novel coupler for lengths of detonating fuse having an explosion-retarding element devoid of the foregoing disadvantages. Another object of this invention is to provide an explosion-retarding and connecting means for lengths of detonating fuse having improved functioning characteristics. A further object of this invention is to provide an explosive device adapted to be interposed between lengths of detonating fuse for reliably retarding the initiation of the second length thereof under the conditions of moisture often encountered at blasting sites and without precise assembly of the device with the lengths of detonating fuse being required. Another object of this invention is to provide a device for connect-

ing lengths of detonating fuse and for retarding the initiation of the second length of detonating fuse which does not require precise assembly with the fuse to be operative and which can be furnished to the blasting trade without detonating fuse attached thereto.

The foregoing objects as well as others will become apparent from the following description with reference to the accompanying drawing in which:

Figure 1 illustrates, in a longitudinal sectional view, 0 one embodiment of this invention attached to lengths of detonating fuse;

Figure 2 illustrates, in a fragmentary side view, partially in section, another embodiment of the invention having a different type of centerfire percussion type primer.

5 Figure 3 illustrates, in a fragmentary side view, partially in section, another embodiment of the invention having a rimfire primer; and

Figure 4 illustrates, in a fragmentary side view, partially in section another embodiment of the invention having a stab initiated type primer.

Generally speaking, the objects of this invention are accomplished by providing a coupler for lengths of detonating fuse having an explosion-retarding element which includes a percussion type ignition assembly. Preferably, the invention provides a tubular coupling device for detonating fuse which contains an explosion-retarding element having a percussion ignition assembly adjacent one end thereof, a detonating charge adjacent the other end and a delay means interposed between the igniter and the detonating charge.

Ordinarily, in practicing this invention, in order to facilitate assembly of the various components of the device, it is preferred to make the explosion retarding element by pressing the detonating explosive charge and a suitable delay composition charge in a conventional detonator case, to insert a cylindrical ferrule having one end open and having a perforated bottom inside the detonator case and adjacent the delay composition, and to thereafter close the open end of the detonator case by inserting a conventional shotgun cartridge primer assembly. Such an assembly of battery cup, anvil and primer cup containing a suitable priming composition is ideally suited for the purpose because it is not only capable of igniting the delay composition but it also has dimensions such that it can be readily assembled with a conventional detonator case. In order to insure that no moisture can enter this assembly, it is preferred to lacquer the battery cup before it is inserted in the detonator case. After insertion of the primer, the entire assembly is dipped in a suitable lacquer or other sealing material. The resulting assembly is then placed in a suitable tube adapted to fit over the ends of lengths of detonating fuse, a firing pin is properly positioned within the tube adjacent that end of the assembly having the percussion type primer and indentations are placed in the tube wall near each end of the tube to stop the detonating fuse when it is later inserted in the tube.

In order further to clarify the invention the following is a description of one embodiment thereof with reference to the accompanying drawing:

In the embodiment shown in Figure 1, about 3 grains of cyclonite 1 are pressed in a conventional aluminum detonator case 2 under a load of about 80 pounds dead weight. Immediately above the cyclonite (cyclotri-methylenetrinitramine) 1, separate charges of about 2½ grains of lead azide 3, about ½ grain of lead styphnate 4 and a charge of about 3.9 grains delay composition 5 composed of about 66% methallic lead powder, about 25% selenium powder, about 4% potassium chlorate and about 5% barium nitrate are each pressed under similar pressures. An aluminum ferrule 6 having a central perforation 7 in the bottom thereof and of such diameter

as to form a slidable fit in case 2 is placed over the delay composition and a shotshell primer designated generally by the numeral 8 composed of a battery cup 9, primer cup 10 containing priming mix 11 and anvil 12 is inserted in the mouth of the detonator case 2. This shotshell primer 8 is dipped in a nitrocellulose lacquer which is permitted to dry before it is inserted in the detonator case 2. After primer 8 has been properly positioned in the mouth of the detonator case 2, the mouth of the entire assembly is dipped in the nitrocellulose lacquer to insure waterproofness. The length of aluminum ferrule 6 is predetermined in order to insure that the detonator 2 is completely filled with the various components placed therein.

The assembled detonator is positioned in aluminum tube 13 such that the end containing charge 1 is about $\frac{1}{8}$ inch from one end of the about $4\frac{1}{2}$ inches long tube 13 having an outside diameter of about 0.27 inch. An annular ring 14 is formed in the tube wall to secure the assembled detonator in place. Firing pin 15 is positioned about $\frac{1}{8}$ inch from primer cup 10 and two or more indentations 16 are formed in the tube wall to lock the firing pin in place. Annular ring 17 is formed in the tube wall to be used later by the operator to predetermine the proper distance to which detonating fuse 18 should be inserted.

In operation, one length of detonating fuse 18 is inserted until the end thereof abuts against annular ring 17 and annular crimp 26 is formed in the wall to secure detonating fuse 18 within the assembly. A second length of detonating fuse 19 is inserted in the other end of tube 13 and in contact with the base of case 2. Annular ring 20 is formed in the wall of tube 13 to secure fuse 19 in position. Upon detonation of the fuse 18 gases accumulate in the space 21 behind firing pin 15 and when sufficient pressure has been developed to break the lock provided by indentations 16, firing pin 15 is driven into primer cup 10, compressing priming mix 11 between anvil 12 and the wall of primer cup 10. Delay mix 5 is thus ignited and after the predetermined time interval afforded thereby, in this particular embodiment about 0.05 second, the explosive charges 4, 3 and 1 are initiated with subsequent initiation of detonating fuse 19.

In the embodiment shown in Figure 2 a tube 13 similar to that in the embodiment of Figure 1 is provided with a firing pin 15 secured in place by means of indentations 16 in the wall of the tube 13. Spaced about $\frac{1}{8}$ inch from the striking point of firing pin 15 is a conventional centerfire primer such as used in rifle and pistol cartridges and designated generally in the drawing as numeral 80. Primer 80 is composed of primer cup 100 containing priming mix 111 and anvil 121 which rests against the end of ferrule 6. Primer assembly 80 and ferrule 6 are shown enclosed in detonator case 2. Annular indentations 14 secure the assembled detonator in place in tube 13. Priming mix 111 may be any suitable priming mix used in rifle and pistol cartridges.

In the rimfire type embodiment illustrated in Figure 3, tube 13 contains a properly positioned firing pin 252 having an annular protuberance 24 designed to be driven against the rimfire cap 200 containing priming mix 211. Cap 200 may be provided with an annular flange similar to that utilized in rimfire rifle and pistol cartridges as an extraction flange and this flange may extend over the mouth of detonator 2 in order to aid in water-proofing the detonator assembly. The mouth of cap 200 is butted against the open end of ferrule 6 and the entire assembly within detonator case 2 is such that cap 200 is rigidly supported in order to insure that priming mix 211 will be initiated when struck by firing pin 252.

In the embodiment of Figure 4 illustrating a primer of the stab-initiated type, a detonator case 2 is charged with a base charge of suitable explosives such as cyclonite 1, and an initiating charge of lead azide 3, a delay composition 5 and a primer 311. This explosive train is enclosed within detonator case 2 by placing a suitable washer 22,

such as one cut from aluminum foil, in the mouth of case 2 and thereafter turning the end of the case 2 over the washer 22 to secure it in place. Slidable firing pin 15 is provided with a pointed protuberance 23 and is properly positioned in tube 13 by means of crimp 16. The gases developed by the detonation of the length of detonating fuse back of the firing pin 15 drive the firing pin into contact with detonator case 2 forcing protuberance 23 into mouth 27 of case 2 and through washer 22 into primer 311. The primer is initiated by the penetration of protuberance 23 and ignites delay mix 5 which in turn ignites the initiator charge 3 and base charge 1. In some embodiments of this type, a ferrule 6, such as illustrated in Figure 1, may be placed between the primer 311 and delay mix 5. Washer 22 can be made from other metal foils such as lead or from paper, plastics or other suitable materials.

In the foregoing embodiment, priming mix 11 is about $\frac{1}{10}$ grain of a mixture of about 35% potassium chlorate, 17% lead sulfocyanate, 30% antimony sulfide, 15% calcium silicide and 3% trinitrotoluene together with about $\frac{1}{10}$ % gum tragacanth or other suitable binder. The particular composition of the priming in the various embodiments is not critical, however, and conventional priming compositions containing potassium chlorate or other suitable oxidizer such as, for example, potassium nitrate, barium nitrate, lead peroxide, and the like, with suitable explosives, such as, lead styphnate, lead azide, tetrazene and the like can be utilized. Particles of glass or other equivalent abrasive material should be used in rimfire primers of the type illustrated as 211. Fuels such as powdered aluminum and the like can be substituted for all or part of the antimony sulfide and calcium silicide. In fact, any standard percussion type primer suitable for igniting the propellant in conventional cartridges for shotguns or other small arms, or in stab-initiated detonators, is suitable. A primer containing normal and basic lead styphnate, aluminum, antimony sulfide and barium nitrate is an example of a suitable primer for the embodiment illustrated in Figure 4.

The embodiments of Figures 2, 3 and 4 are, of course, assembled with lengths of detonating fuse in the same manner as the embodiment of Figure 1.

Various other well known explosives may be substituted for the explosive charges 1, 3 and 4 shown in the foregoing embodiments. For example, mercury fulminate, mixtures of mercury fulminate and potassium chlorate, diazodinitrophenol, tetryl, nitromannite and the like may be utilized in some embodiments alone or in mixtures thereof. Indeed, it is contemplated that charges 1, 3 and 4 may be replaced with a single charge of an explosive such as tetryl, cyclonite, nitromannite or trinitrotoluene or the like in some embodiments of the invention. The weight of the various explosive charges is not critical, but it is preferred that the assembly be at least equivalent in strength to a standard Bureau of Mines No. 6 detonator having a charge of one gram of a 90-10 mixture of mercury fulminate and potassium chlorate but good results can be obtained if the assembly has a greater power than that of the Bureau of Mines' detonator.

Other suitable delay powders may be substituted for delay composition 5 and the amount used will vary with the time interval required. In most instances, however, a delay of from about 0.03 to about 0.05 second will be required in practice. A blend of barium peroxide and magnesium, barium peroxide and selenium, barium permanganate and antimony, or charges of black powder and the like may be utilized. In fact, many other known gas-producing compositions are suitable for the purpose. Moreover, some delay between the detonation of the lengths of fuse will be obtained from the assembly even if no delay mix or detonating charge is included so such a device is within the purview of this invention. In this type of device not containing a delay mix, the interval between detonations is dependent upon the length of the

space between the firing pin, the depth of the crimp holding the firing pin in place and the distance between the primer and the detonating fuse.

It is essential, for best results, that some space be provided between the closed end of the firing pin and the detonating fuse. It has been found that, in the absence of such space, often no delay will be achieved between the ignition of the first length of detonating fuse and the ignition of the second length thereof. This space may be provided as shown in Figure 1 or the length of the firing pin may be sufficient to extend to the fuse. In the latter embodiment, the required space is provided within the firing pin. It is also necessary, for best results, that space be provided between the point of the firing pin and the primer assembly in order to insure that the firing pin will strike the cap with sufficient force to properly initiate the priming composition. In embodiments adaptable for coupling commercially available detonating fuse having a diameter of from about 0.2 to 0.225 inch, it is preferred that the outside diameter of the tube 13 be about 0.267 inch and that the thickness of the sidewalls of tube 13 be about 0.017 inch. As stated above such a tube can be conveniently about 4.5 inches long, although tubes of other dimensions can be utilized. In such a tube, space 21 may be about one inch, space 25 about $\frac{1}{8}$ inch and annular ring 17 may be located $1\frac{5}{16}$ inch from the end of tube 13. Tube 13 may be made of any material adapted to have indentations formed in the wall thereof. For example, it may be made of aluminum, copper, copper-zinc alloys, synthetic resins, waterproofed paperboard or laminated paper or other similar materials.

The device provided by this invention is suitable for use with various types of detonating fuse. It has been found most advantageous, however, for use with detonating fuse similar to that known to the trade as Primacord. Such a detonating fuse has a core of high velocity explosive, usually pentaerythritol tetranitrate, enclosed in an outer case of fabric or metal which may or may not be coated with a waterproofing material such as a nitro-cellulose base lacquer. Such a fuse may detonate at a velocity in the neighborhood of 20,000 feet per second.

It is to be understood, of course, that although it is preferred for convenience and ease of assembly to press the explosive charge, delay composition and percussion type igniter in a detonator case such as described in detail above, it is possible to position them in tube 13 without use of the detonator case, provided the charges are properly pressed therein and, consequently, such a construction is contemplated by this invention. In some instances, the flange at the mouth end of a conventional shotshell battery cup may be too large to fit properly in the detonator case. Under such conditions, it will be necessary to clip or otherwise trim the flange to the proper diameter to form a snug fit within the detonator case 2. It is also conceivable that ferrule 6 may be eliminated entirely and that the percussion type igniter can be properly positioned in tube 13 or in the mouth of detonator 2 by other means such as by forming an annular groove in the wall

of detonator case 2 at a predetermined location such that the base of battery cup 9 will rest against it when properly located in the mouth of case 2. Although it is preferred, for the convenience of the user of the device, to include means for stopping the fuse before it contacts the firing pin, the ring 17 or other means for stopping the fuse may be omitted from some embodiments provided care is taken by the operator to insert the fuse to the proper depth.

- 10 Many other variations in details of assembly may be made by those skilled in the art without departing from the spirit of this invention except as limited by the appended claims. While use of this device is primarily advantageous in commercial blasting operations it is to be understood that it may be used in any type of operation wherein two or more lengths of detonating fuse are to be initiated successively after predetermined delay periods.

What is claimed is.

- 20 1. A device for joining a first length of detonating fuse to a second length of detonating fuse in end-to-end relationship and for retarding the initiation of the second length of fuse a predetermined time interval after detonation of the first length of fuse, said device comprising a tube adapted to be slipped over the adjacent ends of the first and second lengths of the detonating fuse, a firing pin slidably mounted in said tube adjacent the end of the first length of detonating fuse, an explosion retarding element within the tube having a primer positioned between the firing pin and the second length of fuse and spaced from the firing pin, a delay composition in the tube in a position to be activated by the primer and a detonating charge interposed between said delay composition and the end of the second fuse, and means for confining the gases developed by the first length of fuse behind said firing pin and for preventing movement of said pin at less than pressure sufficient for driving the firing pin into said primer with an initiating force.

- 25 2. The device of claim 1 wherein said primer is a percussion cap.

- 30 3. The device of claim 1 wherein said primer is stab initiated.
